UNITED STATES PATENT OFFICE.

HANS A. FRASCH, OF NEW YORK, N. Y.

PROCESS AND APPARATUS FOR PRODUCING HYDROXIDS OF METALS BY MEANS OF AMMONIA.

1,135,785.

Specification of Letters Patent. Patented Apr. 13, 1915.

Application filed April 10, 1913. Serial No. 760,302.

To all whom it may concern:

Be it known that I, HANS A. FRASCH, a citizen of the United States, residing at New York, in the county of New York and State of New York, have invented a certain new and useful Improvement in Processes and Apparatus for Producing Hydroxids of Metals by Means of Ammonia, of which the following is a full, clear, and exact description.

This invention relates to the recovery of hydroxids of metals from their solution, and more particularly of metals whose hydroxids are soluble in ammonia and react with a salt of ammonia.

In order to illustrate my invention I will describe it as applied in the production of the hydroxid of nickel.

It is well known that nickel ammonium chlorid or sulfate can be decomposed by water to nickel hydrate and ammonium chlorid or sulfate. The nickel hydrate obtained by this reaction, as well as by other well known methods, is of bulky and slimy nature and difficult to wash and separate from the filtrate or liquid in which it is suspended. Further, during the evaporation and recovery of the ammonia by boiling, the nickel hydrate reacts with the ammonium chlorid and reverts to nickel chlorid and ammonia; and similar difficulties are experienced in every instance where the hydrate of a metal is precipitated from a solution of a salt of a metal by means of ammonia. My invention overcomes these difficulties, yielding heavy and granular oxids or hydrated oxids which render them of greater value for the production of pigments and carbonates; and in case of nickel, when the hydrate is used for the production of alkali, such nickel hydrate reacts more promptly and assures higher yields of alkali. Besides, my invention permits precipitating by ammonia completely all the nickel or other metals which may be in a solution in much shorter time than otherwise would be required, while at the same time the ammonia may be recovered and again utilized.

Any suitable apparatus may be used for carrying out the process of this invention, and for illustration I have herein shown two forms of apparatus, without however there-

by limiting the invention to mere details, since these may be varied within the requirements of the practice adopted.

In the accompanying drawings, illustrating the invention, in the two figures of which like parts are similarly designated, Figure 1 is a diagrammatic vertical section of one such apparatus, and Fig. 2 is a similar view of another.

The still 1, its heating coil 2, and the condenser 3, may be of any approved construction. In the apparatus shown in Fig. 1, a dephlegmator column 4 is interposed between the still and condenser, and these three parts are in open communication. 5 is a catch-basin for the condenser. 6 is the supply pipe for the still. 7 are the water circulating pipes for the condenser, by which it may be kept at the desired temperature. 8 is a pipe for conveying away from the condenser excess vapor, to another condenser, or an absorber, or other vessel or receptacle, not shown. Pipe 8 is connected by pipe 9 with a circulating pump 10, and this pump is also connected by pipe 11 with the still. The catch-basin 5 may be connected with that portion of the pipe 11 which enters the still, by means of the pipe 12 and its valve 13, and the valve 14 on the pump side of the pipe 11.

In the apparatus shown in Fig. 2, the still is connected with the upper end of a primary condenser 15, by a pipe 16. This condenser is interposed between the still and the condenser 3 and connected to both. On condenser 15 is a safety or back-pressure valve 17 by means of which the pressure in the still and condenser may be regulated. Condenser 15 has the pipe 18 opening into the still to return thereto the condenser fluid. The condenser 3 in this arrangement becomes a secondary condenser. It has a bottom connection 19 with a receptacle 20 to care for the reflux condensation, and also a side connection 21 with said receptacle to allow the air to escape from the receptacle to the condenser. The receptacle 20 is connected by the pipe 22 with pipe 23 leading into the still, and this pipe 23 has valves 24 in it arranged upon opposite sides of the pipe 22.

The condensed ammonical liquor accumulating in the receptacle 20 may be utilized

during further operations and introduced into the still by way of the pipes 22, 23, or it may be conducted through pipe 23 to an absorber and there utilized.

To carry out my invention, for example in recovering nickel hydrate from nickel chlorid, or nickel ammonium chlorid as practised in the manufacture of caustic soda, I add the nickel salt to water, or, as I prefer, to a solution of calcium chlorid containing ammonium chlorid and free ammonia, preferably in proportion of two equivalents of the nickel salt to be treated. By application of heat free ammonia is driven off, to be recovered in the usual manner, and the hydroxid of nickel is gradually precipitated. To avoid undue reversion of the hydrate to nickel chlorid, I add during the distillation of the ammonia, constantly or periodically, free ammonia to the boiling fluid. For this purpose I prefer to employ for the recovery of the ammonia, a reflux condensing system, as shown in Fig. 1, which I keep at a temperature to assure sufficient condensation of ammonia in the reflux liquid to maintain the presence of a desired quantity of ammonia in the distilling fluid, such as may be required by the nickel yet in solution in the fluid. In place of supplying the boiling fluid with ammonia by the return of reflux condensation, I may introduce into the boiling fluid ammonia in the form of gas, or in any other form, coming from the distilling system itself, or from an outside source. Again, I may conduct the boiling under pressure and thereby increase the amount of free ammonia retained in the boiling fluid, as shown in Fig. 2. The boiling and addition of ammonia may be continued until all the nickel or any part thereof is precipitated. To supply the free ammonia to the boiling fluid, I may also add, continuously or periodically, any equivalent alkali which will react with the ammonium chlorid in quantities to assure the presence of a desired amount of free ammonia in the fluid.

While I select for purpose of illustration the recovery of nickel hydrate from nickel ammonium chlorid, I do not limit the application of my invention to this particular compound. The invention may also be employed for recovery of nickel hydrate from other salts of nickel, such as the sulfate or nickel ammonium sulfate, in which case ammonium sulfate may be substituted for the chlorid. It may also be used in the production of the hydrate from a solution of the salts of any other metal, such as lead, copper, cobalt, or iron.

To practice my invention in the apparatus of Fig. 1, I proceed as follows: Into the distilling vessel 1, which is supplied with steam coils 2, I introduce through supply pipe 6

a quantity of a solution of calcium chlorid containing ammonium chlorid and free ammonia, together with the nickel salt, or with a solution of any other salt of a metal from which the hydrate is to be obtained. Steam is then admitted to coil 2 and the contents of the still are heated to boiling. The ammonia and water evaporating during the boiling operation pass through the dephlegmating column 4 and the catch-basin 5 to the condenser 3, which latter is supplied with water through pipes 7, by means of which the condenser 3 is kept at any desired temperature. The condensed steam saturated at a selected temperature with ammonia returns to the catch-basin 5, while the excess of the ammonia vapor coming from still 1 beyond that which the condensed steam could absorb at the temperature existing in the catch-basin 5, passes on through pipe 8 for further condensation, if necessary, or to an absorber, to be there recovered in the usual manner and used again in further operations. The valve 13 being opened, part or all of the contents of the catch-basin 5 may be allowed to return to the still 1, thus supplying fresh quantities of ammonia to the contents of the still 1, at any time it may be desired; or the valve 13 may be so regulated that constantly and continuously a part only, and as much as is desired, of the ammoniacal liquor contained in the catch-basin returns to the still proper by way of pipe 11, while the rest of the ammoniacal liquor from the condenser and catch-basin flows over the catch-basin, or by a special conduit, through the dephlegmator 4, where the ammonia is again volatilized. The boiling of the fluid in still 1 and addition of ammonia through pipe 11 is continued until all or as much of the nickel or other metal as is desired is precipitated. The valve 13 is then closed and the contents of the still 1 are removed through a suitable outlet and the hydrate is then separated from the still liquor by filtration or by any other well-known means. The still liquor or filtrate may then be allowed to cool and the ammonium chlorid which was formed during the operation, or as much of it as is desired, may be allowed to crystallize; or it may be treated while yet hot with lime and returned to the process, the ammonia being recovered during the following operation.

Instead of supplying the still 1 with ammonia during the boiling process by means of the reflux condenser liquid, I may also close the overflow valve 13 and supply the ammonia to the still 1 in form of vapor from pipe 8 by means of the circulating pump 10, pipes 9 and 11, and valve 14. This method of practising my invention is not limited to this particular apparatus, for,

as already stated, I may also conduct the boiling operation under pressure as shown in Fig. 2 and thereby retain in the boiling fluid in the still a greater amount of ammonia than would be possible if the boiling were conducted at atmospheric pressure.

It is understood that the terms "hydroxid" and "hydrate" are interchangeable, and they are so used herein.

10 What I claim is:—

1. The method of precipitating hydrated oxids of metals from solutions of their salts by ammonia, by boiling in presence of an ammonium salt until the oxids are precipitated while maintaining the solution alkaline with ammonia, substantially as described.

2. The method of precipitating oxid of nickel from a solution of a salt of nickel by ammonia, by boiling in presence of an ammonium salt until the nickel oxid is precipitated while maintaining the solution alkaline with ammonia.

3. The method of precipitating nickel oxid from a solution of nickel ammonium chlorid, by boiling in presence of a solution of ammonium chlorid until the nickel oxid is precipitated while maintaining the solution alkaline with ammonia.

30 4. In the process of producing hydrated oxids of metals by means of ammonia, boiling a solution of the salt of a desired metal in presence of a salt of ammonia and free ammonia, condensing the aqueous ammonia-cal vapor evaporated during boiling and returning sufficient of the condensate to keep the boiling solution alkaline while the oxid is being precipitated.

5. In the process of producing hydrated oxids of metals by means of ammonia, boiling a solution of the salt of a metal in presence of ammonium chlorid and free ammonia, concentrating the vaporized ammonia by means of dephlegmation, and re-

turning part of the dehydrated ammonia to keep the boiling solution alkaline while the oxid is precipitating.

6. In the process of producing oxids of metals, boiling a solution of a salt of a desired metal in presence of a salt of ammonia and free ammonia under pressure, condensing more or less of the ammonia during boiling and returning sufficient of the condensate to the boiling solution to keep it alkaline.

7. An apparatus for the precipitation of the hydroxids of metals from their solutions by means of ammonia, consisting of a distilling vessel and a condenser, a receptacle located between the distilling vessel and condenser and provided with an opening for the passage of the vapor, an outflow for the condenser fluid, and means to regulate the outflow and the return of the condenser fluid to the distilling vessel.

8. An apparatus for the precipitation of the hydroxids of metals from their solutions by means of ammonia, consisting of a distilling vessel, a condenser, and a dephlegmating column provided with means to remove from the column all or parts of the return fluid coming from the condenser, and means to regulate the return of such fluid to the body of the distilling vessel.

9. An apparatus for the precipitation of the hydroxids of metals from their solutions by means of ammonia, consisting of a distilling vessel, a condenser, and a dephlegmating device provided with means to abstract ammonia gas from the apparatus, and means to return and introduce the ammonia gas into the body of the still.

In testimony whereof I have hereunto set my hand this 10th day of April A. D. 1913.

HANS A. FRASCH.
